UNITED STATES PATENT OFFICE.

CARL TH. EHNINGER, OF KIRCHHEIM, GERMANY.

PAPER-CUTTING DEVICE.

SPECIFICATION forming part of Letters Patent No. 788,196, dated April 25, 1905.

Application filed April 11, 1903. Serial No. 152,256.

To all whom it may concern:

Be it known that I, CARL THEODOR EHNINGER, a subject of the King of Würtemberg, residing at Kirchheim, Würtemberg, German Empire, have invented certain new and useful Improvements in Paper-Cutting Devices, of which the following is a specification.

The present invention has reference to improvements in paper-cutting devices, and relates more especially to a device for cutting lengths off a supply-roll by means of a thin wire; and the object of the invention is to provide a paper-cutting device for the purpose specified of simple and durable construction and without a cutting-tool, such as shears or a knife-blade, which constantly requires resharpening to keep in good working condition.

In the accompanying drawings, Figure 1 represents a perspective side elevation of a vertical paper-cutter according to my invention. Fig. 2 represents the upper and lower part of the apparatus, partly in section; and Fig. 3 is a plan view.

The bottom plate *a* and the cross-beam *b* are rigidly connected by means of the pillars *c d*. The axle *e*, with foot-plate *h*, is rotatably journaled in the plate *a* by means of the pointed screw-spindle *f* and in the cross-beam *b* by means of the pointed hand-screw *g*. The axle *e* carries the paper-supply roll, which rests upon the foot-plate *h*, as shown in Fig. 1. At the upper part of the axle is provided a ratchet-wheel *i*, which is engaged by the spring-pawl *k*, secured in the cross-beam. This spring-pawl serves to prevent backward rotation of the supply-roll and at the same time acts as a brake. A knob *u* is secured on the pawl for the purpose of temporarily lifting the pawl out of engagement with the ratchet-wheel. To the cross-beam is attached an arm *l*, which journals the upper end of the guide-roller *m*, the lower end of which is journaled in the bottom plate *a*. The cutting-tool consists of a thin steel wire *o*, secured with its lower end in the bottom plate and having a handle *q* at its upper end. When not in use, this handle rests upon the cross-beam, the wire passing through a slot *p* therein. In front of the wire in its position of rest is provided a slot *n* in the pillar *d*, and parallel to

this slot is arranged a guide-wire, a string, or a strip of wood or other suitable material *r*.

In operation the paper is unrolled, passing over the roller *m*, between the guide member *r* and the pillar *d*, in front of the slot *n*, and is easily cut by the wire *o* being pulled through the slot *n*, as shown in Fig. 1. For measuring off definite lengths of paper a measuring-rod *t* may be provided. If only a definite distance is to be cut into the paper, an adjustable stop may be provided in the pillar *d*. The lower end of this wire *o* may be yieldingly secured, as shown in Fig. 2, or its upper end within the handle in a similar manner. 65

It is obvious that the device may be constructed with the paper-roll and the other parts horizontally instead of vertically, as shown.

What I claim, and desire to secure by Letters Patent, is—

1. A paper-cutting device, comprising a frame, a supply-roll rotatably journaled in said frame, a cutting-wire secured with its one end to said frame and adapted to be pulled with its free end through a slot in said frame, and means for suitably guiding the paper in front of and past the said slot, substantially as and for the purpose set forth. 75

2. A paper-cutting device, comprising a frame, a supply-roll rotatably journaled in said frame, means for ordinarily preventing backward rotation of said supply-roll and for braking its forward rotation, a cutting-wire secured with one end in said frame, a handle at the other end of said wire, the wire adapted to be pulled through a slot in said frame, means for suitably guiding the paper off the supply-roll close to and past the said slot in the frame, means for retaining the free-handled end of said wire in its inoperative position, and means for measuring off definite lengths and widths of paper, substantially as set forth. 90

In testimony that I claim the foregoing as my invention I have signed my name in presence of two subscribing witnesses.

C. TH. EHNINGER.
